UNITED STATES PATENT OFFICE.

HILLES C. JONES, OF ALLENTOWN, NEW JERSEY.

COMMUTATOR.

1,318,208.

Specification of Letters Patent.

Patented Oct. 7, 1919.

Application filed February 3, 1919. Serial No. 274,657.

To all whom it may concern:

Be it known that I, HILLES C. JONES, a citizen of the United States, residing at Allentown, in the county of Monmouth and 5 State of New Jersey, have invented new and useful Improvements in Commutators, of which the following is a specification.

This invention relates to commutators or timers for use in connection with internal combustion engines of that type ordinarily used as the motive means for vehicles, such as automobiles, and particularly to the class of commutators or timers used in connection with the Ford engine or motor to control the sparking circuits. Ordinarily, the connecting wires between the commutator or timer and the spark plugs of the cylinders of a Ford engine or motor are exposed at points adjacent to the commutator which in 10 the Ford machine is located at the front of the engine or motor in rear of the fan. These exposed connecting wires become begrimed with oil and grit and are rapidly worn to such extent as to frequently expose 15 the copper wires within the insulation and set up short circuits with obvious disadvantages in the operation of the commutator and the sparking plugs. In view of the disadvantages of the wires adjacent and connected to the commutator of the class specified, the improved commutator embodying the subject-matter of the present invention has been devised, and the object, therefore, of the improvement is to protect the wires 20 leading from the commutator by concealing and covering them in such manner as to avoid wear and deterioration thereof and also to have them lead out from the commutator at one point in a group without resorting to the usual connection at different 25 points around the periphery or outer side of the commutator casing and thereby preserve the connections between the commutator and the engine cylinders and render 30 their service more durable.

With these and other objects and advantages in view, the invention consists in the construction and arrangement of the several parts which will be more fully hereinafter 35 described and claimed.

In the drawing:

Figure 1 is a top plan view of a commutator or timer embodying the features of the invention and showing the inclosing means 40 for the connections and the wires broken through to shorten the same.

Fig. 2 is a horizontal section through the improved commutator.

Fig. 3 is a transverse vertical section on the line 3—3, Fig. 1.

Fig. 4 is a sectional view of the casing taken on the line 4—4, Fig. 1 and illustrating the ring or annulus therein in side elevation.

The numeral 5 designates a casing of the usual form adopted in the construction of a commutator as applied in connection with a Ford engine or motor, the casing 5 including a conical top 6 having at one point therein an opening 7 normally closed by a screw plug 8, the opening 7 being adapted for the purpose of oiling the commutator. Within the casing 5 is an insulating ring or annulus 9 which, in the present instance, is preferably formed of fiber, and at different points therearound are contact points 10, 11, 12 and 13 with which a brush and roller arm 14 coact, as usual, and particularly shown in dotted lines by Fig. 2. The brush and roller arm are operated as usual and well understood in this particular type of commutator or timer. The contacts 10, 11, 12 and 13 are of segmental contour and have their inner sides exposed for engagement with the roller of the roller arm in the course of making and breaking the circuits relatively to the several cylinders of the engine or motor. Each contact has a metal or conducting stud or pin 15 projecting outwardly therefrom through the ring and supplied with a nut 16, the pin and nut serving as a binding post. In the present instance the nut and pin are inclosed within the casing 5 instead of being located exteriorly, as in the common form of the Ford commutator. At the points where the nuts 16 engage the pins or posts 15, the ring or annulus 9 is provided with outwardly opening recesses 17 to receive the nuts and remove the latter out of contacting adjacency with respect to the metal casing 5 surrounding the same, and, in addition, the ring or annulus is formed with circumferential grooves 18 and 19 in which the insulated wires *a*, *b*, *c* and *d* are embedded or housed, the said wires being drawn around the outer side of the ring or annulus and closely held within the grooves, as clearly shown by Figs. 2, 3 and 4. Though the wires are insulated they are held within the grooves 18 and 19 at a distance from the inner surface of the surrounding casing 5, and at a suitable point

in the latter casing a screw-threaded opening 20 is formed to receive a hollow screw plug or coupling 21 attached to one end of a flexible tube 22 and whereby all of the 5 wires are inclosed in the form of a cable or loom and are thus led up to the point of connection thereof with the sparking plugs of the respective cylinders, it being understood that the tube 22 will be made as long 10 as found necessary to inclose the wires for a greater portion of their length and particularly at the point of adjacency to the casing 5 where all of the wires are led out together through the screw-threaded opening 20 within the tubular screw plug or coupling 21. It will be understood that the ring or annulus 9 will be fixed within the casing 5 by any suitable means, and before 15 said ring or annulus is inserted within the casing the wires will be connected thereto and extend through the screw-threaded opening 20 and also through the plug or coupling 21 and tube 22. By this means the wires emanating from the commutator 20 will be protected and shielded against wear and especially be prevented from having an accumulation of oil settling thereon which is driven back by the operation of the fan and settles on the wire connections in the 25 ordinary arrangement of said connections with relation to the commutator as commonly adopted in the Ford automobile, and as a consequence wear of the wire connections will be reduced to a minimum and 30 short-circuiting of worn wires and the motor trouble incident thereto will be avoided. 35

The improved commutator may be readily constructed and installed, and in view of the advantages incident to the use thereof 40 will render the general operation of the motor more satisfactory and effective.

What is claimed is:

1. A commutator of the class specified having a casing, an insulating ring secured 45 within the casing and carrying the usual contacts, the ring being formed with separated circumferential grooves in the side edge of the ring between the top and bot-

tom sides of the ring and the casing having an opening therethrough at one point, wire 50 connections attached to the contact points and housed in said separated grooves and extending out from the casing through the said opening, the casing forming the outer closure for the grooves, and an inclosing 55 tube for the wires having a hollow plug inserted in the said opening and fully inclosing the wires emanating from the casing.

2. In a commutator of the class specified, a casing having an opening therein, a tubular plug fitted in said opening and attached to an inclosing tube, an insulating ring secured within the casing and having the usual contacts and having separated grooves in the side edge thereof, and a wire connection for each contact, the wire connections all being drawn around the outer side of the ring in the side edge grooves of the latter and located between the ring and the casing and closely grouped and passed 70 through the opening, the plug and tube.

3. In a commutator of the class specified, a casing, an insulating ring mounted within the casing and provided with the usual contact members, and with separated grooves 75 in the side edge between the bottom and top thereof, pins extending outwardly from the contact members and having nuts on their outer ends, the outer side of the ring having recesses to receive the nuts to prevent 80 contact of the latter within the casing, wires individually connected to the pins and held by the nuts and pressed closely in the separated grooves around the ring and drawn in close group association and passed out 85 through the opening in the casing, and means connected to the casing for inclosing the wires fully from their points of emanation from the casing.

In testimony whereof I have hereunto set 90 my hand in presence of two subscribing witnesses.

HILLES C. JONES.
